UNITED STATES PATENT OFFICE

ANTON E. BOOD, OF CRANSTON, RHODE ISLAND, ASSIGNOR TO UNIVERSAL WINDING COMPANY, OF BOSTON, MASSACHUSETTS, A CORPORATION OF MASSACHUSETTS

TRAVERSING-MEANS FOR WINDING MACHINES

Application filed March 19, 1931. Serial No. 523,894.

This invention relates to an improved traversing means for winding and like machines employed for winding yarn, thread, cord, wire and other strand materials to produce cops, bobbins, cones, coils or packages. In the following specification and claims the term "yarn" is used in a general sense to designate the material to be wound, whatever its nature, and the term "package" to indicate the product produced by the machine whatever the form thereof.

One object of the present invention is to provide a traversing-means for winding machines consisting in a single rotating element which may be operated at a high rate of speed without shock or vibration.

Another object of the invention is to provide a traversing-means of the type specified which displaces the usual bulky and heavy cams and the reciprocating thread-guides and other moving parts connected to be operated therefrom.

Another object of the invention is to provide a traversing-means constituted by a rotating element, such as a roll or drum, having on its peripheral surface a yarn-receiving and guiding groove extending helically in one direction and back in the opposite direction with its convolutions crossing to adapt the yarn to feed through the groove and be traversed thereby from end to end of the package to deposit it in helical turns which form the layers constituting the wound mass.

A particular object of the invention is to provide a traverse-roll of the type disclosed in United States Letters Patent No. 1,749,355 to Franklin Augustus Reece, dated March 4, 1930, which is of simpler construction as regards the formation of the grooves, less expensive to manufacture, yet as efficient in operation for the purposes specified.

Further objects of the improvement are set forth in the following specification which describes a preferred form of construction of the invention and several methods of applying it to use as illustrated by the accompanying drawings. In the drawings:

Fig. 1 is a front elevation of a portion of a winding machine, showing the winding

spindle and rotatable yarn-receiver or cop-
tube on which the package is wound, with the present improved traversing-means applied to use therewith;

Fig. 2 is an end elevation of the machine shown in Fig. 1 and illustrating in addition the arrangement of the supply-cop or bobbin from which the yarn is delivered to a tension-device and thence to the winding mechanism;

Fig. 3 is an enlarged side view of the present improved traversing-means or grooved roll;

Fig. 4 is a similar view showing the opposite side of the roll;

Fig. 5 is a cross-sectional view of the roll taken on line 5—5 of Fig. 3; and

Fig. 6 is a development of the surface of the roll showing the arrangement of the grooves.

In the Reece Patent No. 1,749,355, herein-before referred to, the traversing-means consists of a cylindrical drum or roll having on its peripheral surface a yarn-receiving and guiding-groove extending in helical convolutions in one direction a distance approximately the length of the package to be wound and back in the opposite direction to the starting point with its convolutions crossing each other, and with the sides of the groove at the crossing points chamfered or cut away to prevent the yarn being diverted from that portion of the groove in which it is traveling to an oppositely extending portion of said groove. The oppositely extending portions of the groove are preferably of different depths at the crossing points, or at different levels with respect to the periphery of the roll, to further assist in maintaining the yarn in that portion of the groove in which it is traveling to prevent it being diverted into an opposite portion at the crossings.

In the present invention the chamfering or cutting away of the groove at the crossing points is dispensed with to render the roll simpler to construct and cheaper to manufacture, but in order to insure that the yarn will follow the proper direction of traverse at the crossing points and not be diverted from a portion of the groove leading in one direction to a portion leading in the opposite di-

rection, I have devised a simple yet ingenious method of forming the grooves at their crossing points as will later be more specifically described. Briefly, my improved method of constructing the grooves consists in offsetting portions of the groove which cross another portion or, in other words, by staggering the sections of the groove extending in a certain direction, one with respect to the other, at the points where one portion crosses an oppositely extending portion.

The invention is herein shown as applied to use with a conventional form of winding machine in which the cop or package is driven by peripheral contact with the grooved roll so that this single element provides not only the means for rotating the wound mass, but also means for traversing the yarn longitudinally back and forth thereon to build up the package in overlying layers of helical coils. It is to be understood, however, that the present invention is applicable to winding machines of other types in which the package is driven from a separate roll or wherein it is positively driven from a rotating winding-spindle. It is therefore to be understood that the invention is not limited with respect to its method of application to the winding machine or its mode of operation in connection with the other winding elements thereof.

In the present drawings the winding mechanism is illustrated as comprising a mandrel or spindle for supporting the package to be wound; the present improved traversing means for distributing the yarn on the package; a supply-holder for mounting a cop, bobbin or other form of package from which the yarn is supplied; and a tension-device through which the yarn feeds from the supply and from which it leads directly to the traversing-means or grooved roll. In Figs. 1 and 2 of the drawings, 2 designates the main frame of a winding machine which may comprise a plurality of winding units arranged in gang form along a bed or table 3. A series of cross-arm brackets 4 extend laterally of and are bolted at 6 to longitudinal rails 7 supported from the bed 3, said brackets being provided with bearings for a horizontal drive-shaft 12 which carries a series of the grooved traverse-rolls 15, one for each unit of the winding mechanism. The rolls 15 are keyed or secured fast on the shaft 12 by any suitable means such, for example, as a set-screw 13 shown in Figs. 2, 3 and 5. The present drawings illustrate only one unit of the winding machine, it being understood that all of the units are of substantially the same construction and arrangement.

Referring to Fig. 1, each bracket 4 is provided with housings 9 for annular ball bearings 10 in which the roll-shaft 12 is journaled. The shaft 12 may be driven from any suitable source of power, such as a motor 65 geared or otherwise connected thereto at its

end. The shaft 12 and the drums or rolls 15 carried thereby constitute the only moving parts of the machine, the rolls being preferably continuously rotated and the winding operation being controlled by placing the packages in contact therewith to start the winding and by removing them therefrom to arrest the winding.

The yarn mass or package may be supported on a central core or mandrel constituted by a paper tube or a wooden or fiber-yarn-receiver T such as shown in Fig. 1. The winding machine as herein illustrated is adapted to wind a frusto-conical mass of yarn, generally termed a "cone", and for this purpose the support or yarn-receiver T is of frusto-conical shape as illustrated in Fig. 1. The cone-tube or receiver T is mounted free to rotate on a dead spindle 5 carried at the end of a swinging arm 16 which is pivoted at its opposite end on a stud or rod 17. The stud 17 is secured in a hub 18 at the top of an arm 19 projecting upwardly from the frame member or bracket 4. The main portion of the arm 16 is of forked construction, having two hubs 20 and 21 which pivot on the rod 17, see Fig. 1, and are held in place by a collar 22. The arm 16 has an outer extension 23 which is swiveled at 24 to adapt the spindle 5 to rock or tilt with respect to the axis of the roll 15, whereby to aline the surface of the package with the periphery of the roll in the usual manner as well known to those versed in the art.

As the yarn builds up on the cone-tube or receiver T the latter recedes from the roll 15 with the spindle 5 moving upwardly as provided for by the swinging action of the arm 16. Instrumentalities are generally provided for moving the package away from the roll 15 to arrest the winding operation, the stopping mechanism usually comprising a rod or bar 25 connected to an arm or extension 26 of the spindle-supporting arm 16 as illustrated in Fig. 2 of the present drawings. As the stopping-mechanism of the winding machine constitutes no part of the present invention, however, it is not herein described in detail.

The yarn or other strand material may be supplied to the winding operation in any usual manner and, as herein shown, a supply-bobbin B is mounted at the front of the machine at a height to be readily accessible to the operator in doffing and replenishing the supply. The supply-holder is arranged as next described. Clamped to the legs 8 of the machine are arms or brackets 27 carrying a horizontal rod 28 on which are mounted a plurality of brackets 29, one for each winding unit. Attached to each bracket 29 is a tension-device 30 which comprises a suitable frame-member 31 for mounting a pair of tension-disks 32 held on a cross-pin 33. The tension-device may be of any usual con-

struction and is not herein described in detail as it forms no part of the present invention. Associated with the tension-device is a 5 sub-catcher or yarn-cleaner 34 arranged above the tension-disks 32. Above the sub-catcher 34 is a wire thread-guide 35 through which the yarn y leads to direct it down through the sub-catcher and between the two tension-disks 32, and at the rear of the 10 tension-device is an auxiliary guide or roller 36 around which the strand draws as it feeds up to the winding mechanism.

An arm 39 is attached to the front of the 15 bracket 29 and extends upwardly at an inclination to the vertical to form a support for the supply-holder, represented generally at 40. As herein shown the supply-holder 40 comprises a rotatable hub 41 carrying radial spindles 42 on which the supply-bobbins 20 B are placed, the spindles being adapted to be turned with the hub to bring a bobbin into inverted position with its nose end pointed toward the guide 35 through which the 25 yarn leads. The bobbins B are retained in place on the spindles 42 by means of circular side strips 43 which engage under the head b of the bobbin as the latter is turned into down position.

As the yarn leads up from the tension-device 30 to the traverse-roll 15 it is guided by a thread-bail 45 extending horizontally across the front of the roll 15, slightly below the axis thereof, see Fig. 1. The thread-bail 45 consists of a wire bent into inverted U-shaped with its legs 46 pivoted on cross-pins 47 supported from the machine-frame. The thread-bail 45 may be constituted as a feeler or breakage-lever, being arranged to swing outwardly away from the traverse-roll 40 15 when the tension on the strand is released through breakage or exhaustion of the supply. The thread-bail 45 cooperates with the stopping-mechanism of the machine to initiate the action of the means which raises the package away from the periphery of the drive-roll to arrest the winding operation, the construction and arrangement of this mechanism being in accordance with the usual practice.

The traverse-roll 15 which forms the subject-matter of the present application is preferably in the form of a cylinder having a length several times its diameter. The roll 55 15 may be constructed of metal in the form of a hollow cylinder or it may be made of wood, fiber or composition such as bakelite. When constructed of metal the grooves in the roll may be cast or machined, and when 60 a composition such as bakelite is employed the grooves may be formed in the operation of molding the cylinder. In any case, the present simplified form of the grooves provides for greater facility in manufacturing the rolls either by machining operations

or by molding and therefore reduces the cost of manufacture.

Referring now to Figs. 3 to 6 of the drawings, the improved traverse-roll 15 as herein illustrated is formed with a substantially continuous groove extending helically from one end to the other and back again to the starting point. While the groove, being continuous, has been referred to as a single groove, for convenience of description it will hereinafter be referred to in the specification as comprising two grooves extending in opposite directions and joined at their ends. One groove 50 may be said to start at the point x at the right-hand end of the roll, see Fig. 3, and extending in helical convolutions it encompasses the periphery in three turns or revolutions to a point z at the opposite end of the roll. The other reversely-extending groove 51 starts at the point z and leads back in the opposite direction in three convolutions terminating at the starting point x of the first groove 50. This particular groove formation is described and illustrated by way of example only, it being within the purview of the present invention to provide a groove or grooves having a greater or less number of turns or convolutions extending in each direction in accordance with requirements of the winding to be performed. With the present arrangement, the traverse-roll 15 will operate to traverse the yarn from one end of the package to the other in three turns or convolutions about its circumference to effect what is termed a "three wind" at the start of the winding. In drum-driven machines the peripheral speed of the wound mass remains constant whereas its angular velocity or speed of revolution progressively diminishes during the winding, due to the gradual increase in its diameter, it being taken as a premise that the speed of the driving drum or roll is constant. It will thus be understood that if a package is started with a three wind, for example, as the wound mass increases in diameter the number of winds is reduced and the package may eventually finish with one wind or even a fraction of a wind. In other cases where the package

is rotated at a constant rate by a positively driven winding-spindle the number of winds remains the same from start to finish of the package as will be readily understood by those versed in the present art.

It will be observed from the foregoing, and by reference to Figs. 3, 4 and 6 of the drawings, that the groove 50 leads toward the left-hand end of the roll 15 to traverse the yarn in this direction, while the groove 51 has a reverse lead, or toward the right-hand end of the roll to traverse the yarn back again in the opposite direction; the direction of rotation of the roll being indicated by the arrow in Fig. 2. It will also be noted that with the present arrangement, wherein each groove

115

120

125

130

makes three complete turns about the periphery of the roll, the two grooves will cross each other or intersect at five different points, three on one side of the roll and two on the opposite side, see Fig. 6 which shows a development of the surface of the roll. Starting at the point *x* the groove 50 extends around to the opposite side of the roll 15 where it crosses the groove 51 first at the point 10 *a*, shown in Fig. 4, next on the other side at the point *b*, illustrated in Fig. 3, again at the point *c* intermediate the ends of the roll, once more at the point *d* on the opposite side of the roll and finally at the point *e*, whence it 15 continues to merge with the groove 51 at the terminal point *z*.

As in the traverse-roll of the patent hereinbefore referred to the grooves 50 and 51 in which the yarn is traversed are of different 20 depths where they cross each other, this change in depth being for a purpose as later explained. Each of the grooves 50 and 51 has a normal maximum depth throughout the greater portion of its extent, but where the 25 grooves cross each other one or the other of them is made of relatively slight depth to assist in guiding the strand through the crossover without diversion from the groove in which it is traveling to the groove of opposite direction. The profiling of the grooves is shown graphically in Fig. 5 and their arrangement at the crossovers, as regards their depth, is more specifically explained in reference to their relationship at the crossing 30 points.

In accordance with the present invention the groove 50 extends in a normal helical course from the point *x* to the first crossover *a* where its course is staggered as shown in 40 Figs. 4 and 6. At this point the portion of the groove 50 which intersects the groove 51 at one side thereof is not continued in its true course on the opposite side of groove 51, but, on the contrary, its continuing portion is 45 staggered or offset to the right as illustrated at 52 in Fig. 4. As the groove 50 continues in its portion beyond the crossover *a* it intersects the groove 51 again at the point *b*, see Fig. 3, and at this point its course is also diverted from normal. That is to say, as the groove 50 crosses the groove 51 at the point *b*, instead of continuing in a straight course its portion beyond the groove 51 is again staggered with respect to its first portion or, in other words, offset to the right at 53.

It has been discovered that by thus offsetting the two portions of the groove at the point of their intersection with the reverse groove, the tendency of the strand to become 55 diverted from its course in the groove of a given direction is overcome. This tendency is as next explained. The strand *y*, represented by dotted lines in Figs. 3 and 4, has a tendency to drag on the right-hand edge of the groove 51 or, in other words, to lag in its

traverse to the left in this groove. This lagging tendency would normally cause the yarn to catch on the point *p* extending toward the crossover of the two grooves 50 and 51 and as a consequence thereof the yarn would be diverted from the groove 50 into the groove 51 70 unless some means were provided to prevent this action. In accordance with the present invention, by staggering or offsetting the two sections of the groove 50 where they enter and leave the reverse groove 51 the strand *y* is caused to enter freely into the continuing portion of the groove 50 beyond the crossover and thus its traverse to the left will be continued without interruption. 75

At the next crossover *c*, which occurs on the opposite side of the roll 15 at a point midway between its ends, the groove 50 is continued in its normal course without a break or offset, see Fig. 4, while the opposite groove 51 has its course abruptly altered as later more specifically described, the reason being that at this point the groove 50 is of greater depth than groove 51 so that the strand *y* will not have a tendency to follow into the groove 51. 80 Likewise, at the point *d* the groove 50 continues in a normal course without interruption and again at the crossover *e* the continuing portion of the groove is normal to its main course. 85

Starting at the point *z*, where the direction of traverse is reversed, the groove 51 leads back to the right and at the first crossover *e* this groove has its course diverted by offsetting its continuing portion to the left as 90 shown at 54 in Fig. 4. Again, at the crossover *d* the continuing portion of the groove 51 beyond the groove 50 is offset to the left at 55 and still again at the crossover *c*, as indicated at 56 in Fig. 4. Beyond the crossover *e* the groove continues through the crossovers *b* and *a* in an uninterrupted course to the point *x*. 105

It is to be understood that at the central crossover *c* it is immaterial which one of the 110 grooves is staggered, the arrangement being dependent upon which groove is given the greatest depth at this point. It has before been explained in connection with Fig. 5 that the grooves 50 and 51 are of the same depth 115 throughout the greater portion of their extent, but at the points where one groove crosses the other the profile of the bottom of one of the grooves is raised to a higher level than that of the other groove. In the present 120 form of construction the groove 50 starts at the maximum depth, indicated at 57 in Fig. 5, but where it crosses the groove 51 at the point *a* its bottom makes an abrupt rise near the periphery of the roll, as indicated at 58 125 in Fig. 5. The opposite or continuing portion of the groove 50 also has less depth at the point 59, but the profile immediately descends to give the maximum depth to the groove 50 just beyond the crossover *a*. The 130

grooves 50 and 51 have a similar profiling at the crossover *b*, the groove 50 being of minimum depth and the groove 51 of maximum depth at this crossover; but at the central crossover *c* the groove 50 continues at maximum depth while the level of the groove 51 is raised. Due to this arrangement the groove 50 is not offset in its continuing portion, the strand being guided in the deep portion of the groove 50 so that it is prevented from being diverted into the reverse groove 51 which is of less depth. It will be apparent, of course, that the arrangement of the crossover *c* at the center of the roll could be reversed by having the groove 50 of minimum depth and offset and the groove 51 of maximum depth without any offset.

The method of operation of the complete machine is as next explained. To prepare the machine for winding, a bobbin B is placed on one of the spindles 42 of the supply-holder and turned down into the position shown in Fig. 2 with its delivery end pointing toward the tension-device 30. The yarn *y* is drawn off from the nose of the bobbin, led through the guide 35 and slub-catcher 34 and thence carried down between the tension-disks 32. From the tension-device 30 the yarn is drawn up across the auxiliary guide or roller 36, thence over the thread-bail 45 and its end attached to the cop-tube or receiver T which has previously been placed on the spindle 5. The end of the yarn is usually attached to the cop-tube T by winding a few turns around the base end of the tube in the groove *t* provided for that purpose.

With the machine threaded up in this manner the arm 16 is lowered to place the surface of the cop-tube T in contact with the periphery of the roll 15 which functions as the driving-means therefor. As the cop-tube is placed against the roll 15 it will be rotated thereby and immediately the receiver starts to wind on the yarn the strand will be entered into one or the other of the grooves 50 or 51 in the surface of the roll; it being understood that the roll is continuously driven in the direction indicated by the arrow in Fig. 2.

The yarn *y* is thus automatically entered into the groove in the traverse-roll to be traversed longitudinally of the cop-tube or receiver T in the manner as next explained. It will be understood that the yarn *y* draws across the thread-bail 45 and through the groove in the roll 15 at a tangent to the bottom thereof, feeding to the package at a point of proximity to its point of contact with the periphery of the roll, see Fig. 2. Fig. 1 of the drawings illustrates the parts of the winding mechanism in position after the roll 15 has traversed the yarn *y* from the base end of the tube T to its apex end in three convolutions encompassing the periphery of the tube, and back again in the oppo-

site direction with two convolutions, the return traverse being thus incomplete.

The method by which the strand is traversed and caused to follow each groove 50 or 51 from end to end thereof without being diverted into the reverse groove at the crossovers will now be explained in detail. For convenience of explanation let it be assumed that the strand *y* is feeding through the groove 50 at the right-hand end or starting point *x* of this groove, indicated at *x* in Fig. 3. As the roll 15 rotates in the direction of feed of the strand, or in a clockwise direction as viewed from the right-hand end of the roll, the yarn will follow the groove 50 from the point *x* to be traversed toward the left. That portion of the groove 50 extending from the point *x* toward the first crossover *a* is of maximum depth, as before indicated, and the yarn feeds therethrough with the side of the groove directing its course. As the roll 15 turns to a position as illustrated in Fig. 4 the yarn *y* reaches the crossover *a* and at this point is raised above the normal level of the groove by the abrupt rise of the bottom thereof indicated at 58 in Fig. 5. As the roll 15 continues its rotation with the yarn passing through the crossover *a* there will be a tendency for the strand to lag as it is acted on laterally by the right-hand side of the groove 50. Under such a tendency the yarn will be bent around the end of the wall of the groove 50 and, unless provision is made for intercepting it, it is liable to be caught on the point *p* which projects towards the crossover to divert it into the groove 51. To prevent such diversion of the yarn from its true course the continuing portion of the groove 50 is offset to the right at this point and the strand *y* will find its place in between the walls of this portion of the groove 50 where it leads out from the side of the groove 51; the action of the strand being indicated by the dotted line in Fig. 4. The traverse of the strand is thus continued to the left without interruption at the crossover *a* and the same procedure takes place as the strand passes through the crossover *b* as indicated by the dotted line in Fig. 3 of the drawings.

The groove 50 next crosses the groove 51 at a point equidistant from the ends of the roll and at this crossover its course is normal without any staggering or offsetting of its branches. The groove 50 is of maximum depth where it crosses the groove 51 at the point *c*, whereas, the bottom of the groove 51 is raised at this crossover as previously explained. Since the yarn will pass through the crossover *c* at the lower level it will have no tendency to be diverted into the groove 51. Stated briefly, the strand will be guided by the unbroken side of the groove 50 below the level of the groove 51 so as to retain it in the groove 50. The same is true as regards the crossover *d*, the groove 50 at this

- point being deeper than the groove 51 and therefore acting positively on the yarn without chance of its being diverted into the groove 51. The crossover at *e* is also of the same arrangement as at *c* and *d*, the groove 50 being deeper than the groove 51 at this point and therefore restraining the yarn from being diverted into the shallow portion of the other groove 51 at the crossover. 5
- 10 The yarn *y* is thus caused to be traversed to the full extent from the point *x* to the point *z*, this distance corresponding to the length of the package to be wound. At the point *z* the traverse of the yarn is reversed 15 to cause it to feed back in the opposite direction, or to the right as viewed in the present drawings, the yarn being now guided in the groove 51. At the first point *e* where the groove 51 crosses the groove 50 the continuing portion of the groove 51 is offset to the left as shown at 54 in Figs. 4 and 6. This arrangement of the grooves is the opposite of that at the crossover *a*, the continuing portion of the groove 51 being offset to the left of the opposite section there- 20 of because the tendency of the yarn *y* is to lag or to be retarded with respect to the direction of its movement which is towards the right. 25
- 30 The turning of the roll 15 causes the yarn to travel in the groove 51 from the crossover *e* to the crossover *d* where the formation of the grooves is similar to that at *e*. That is to say, the continuing portion of 35 the groove 51 is offset to the left with respect to its first portion. Through this arrangement the yarn is held to its proper course at the crossover *d*, it being understood that the groove 51 is of less depth 40 than the groove 50 at this point. At the crossover *c* the continuing portion of the groove 51 is also offset to the left and of less depth than the groove 50 so that the action of the yarn in passing through this 45 crossover is the same as previously described. Continuing from the crossover *c* the course of the groove 51 is normal at the crossovers *b* and *a*, see Fig. 6, it having been previously explained that the other groove 50 is offset at these points and raised above the level of the groove 51 which is of maximum depth from just beyond the crossover *c* to the point *z* where its terminus joins the groove 50. 50
- 55 From the above explanation it will be observed that the rotation of the roll 15 causes the yarn to be traversed back and forth on the yarn-receiver or other support coextensively with the length of the package being wound and without chance of the traverse being shortened by diversion of the strand from the groove extending in one direction to that leading in the opposite direction. The operation of the machine is con- 60 tinuous as long as there is a supply of yarn 65

feeding to the package. When an interruption in the supply occurs, due to breakage or exhaustion of the yarn, the winding operation is automatically arrested by raising the package off from the roll 15. After the supply has been replenished and the end pieced up the winding operation is started again by lowering the package into contact with the roll 15. At the completion of the package to the desired size the winding operation is arrested by an automatic sizing device, not herein shown, and the package removed and a fresh yarn-receiver placed on the spindle 5. 70

75 It is to be particularly observed that through the use of my improved traverse-roll the winding mechanism is very materially simplified, the form of construction of the machine as herein shown requiring but one winding element, namely, the roll 15 which acts both to rotate the package and traverse the yarn thereon. No reciprocating or oscillating thread-guides or other moving parts requiring a reversal of motion are employed in the machine and thus it may be operated at a much higher rate of speed to correspondingly increase its rate of production. 80

85 The present improved traverse-roll is of the utmost simplicity as regards the formation of its surface grooves. No cutting away or profiling of the walls of the grooves is necessary, the grooves being of geometric arrangement as illustrated by the diagram showing the development of the surface of the roll in Fig. 6. This provides that the roll may be manufactured by ordinary machining operations with greater speed and economy and without requiring profiling by hand. It also provides for economical manufacture of the rolls if molded or cast. It 90 has been demonstrated that the present form of roll is of high efficiency and capable of guiding the yarn with greater precision and accuracy than the usual reciprocating thread-guide; the yarn being deposited on the package at its point of contact with the roll to prevent the coils from sliding or slipping out of place. Furthermore, the knuckles or bends of the yarn where it is reversed at the ends of traverse are made sharper and more definite so that there is less chance of the coils slipping over the edge of the package and becoming displaced to form what is known as overruns or "cobwebs". 95

100 While the present invention is herein shown in a preferred form of construction and as applied to a certain type of winding mechanism, it is to be understood that variations may be made in the form and structure 105 of the rotating element or roll and its method of application to use without departing from the spirit or scope of the invention. Therefore, without limiting myself in this respect, 110 I claim: 115

1. A traversing-means for winding and like machines comprising a rotatable element having on its peripheral surface a yarn-receiving and guiding groove of oppositely-extending and crossing helices, said groove having staggered portions at the cross-overs to insure the yarn being guided in a predetermined direction. 5
2. A traversing-means for winding and like machines comprising a rotatable element having a peripheral yarn-receiving and guiding groove extending helically in opposite directions with its convolutions crossing each other and with the portions of the groove which intersect a reversely-extending portion thereof disposed in offset relationship on opposite sides of the crossover. 10
3. A traversing-means for winding and like machines comprising a rotatable element having its periphery provided with a yarn-receiving and guiding groove consisting of oppositely-extending crossing helices forming a continuous path for the yarn, with a portion of the groove which intersects a reverse portion of the groove at one side thereof of offset from the continuing portion of the groove extending in the same direction on the other side of the crossing. 15
4. A traversing-means for winding and like machines comprising a rotatable element having a continuous helical yarn-receiving and guiding groove the oppositely-extending convolutions of which cross each other, with portions of the groove extending in a given direction laterally offset one with respect to the other at their point of intersection with an oppositely-extending portion of the groove. 20
5. A traversing-means for winding and like machines comprising a rotatable element provided with a helical yarn-receiving and guiding groove having its convolutions crossing each other, with portions of the groove extending in a given direction offset laterally one with respect to the other on opposite sides of their intersection with another portion of the groove extending in the reverse direction. 25
6. A traversing-means for winding and like machines comprising a rotatable roll having its periphery provided with a helical yarn-receiving and guiding groove of oppositely-extending crossing convolutions, a portion of the groove extending in a given direction being disposed in a staggered course at its point of intersection with the reversely extending portion of the groove. 30
7. A traversing-means for winding and like machines comprising a rotatable element having on its periphery a helical yarn-receiving and guiding groove constituted by a plurality of crossing convolutions extending in opposite directions in a generally normal course, but with a portion of the groove extending in a given direction offset from its 35
- normal course at the point where it crosses another portion of the groove extending in a reverse direction. 40
8. A traversing-means for winding and like machines comprising a rotatable element having its periphery traversed by a continuous helical yarn-receiving and guiding groove extending in opposite directions with its convolutions crossing each other, a portion of the groove at a crossing being deeper than the reversely extending portion of the groove which it crosses, and one portion of the groove having its entering section offset with respect to its continuing section at the point of intersection with a reversely-extending portion of the groove. 45
9. A rotatable traverse-roll having its periphery provided with a yarn-receiving and guiding groove extending from one end to the other and back again in helical convolutions, the convolutions leading in one direction crossing those leading in the reverse direction and intersecting them at different points on the opposite sides thereof. 50
10. A rotatable traverse-roll having a helical yarn-receiving and guiding groove consisting of oppositely-extending crossing convolutions, certain of the convolutions leading in a given direction being normal at the cross-overs and those leading in the opposite direction having portions offset laterally one with respect to the other where they intersect a crossing convolution. 55
